LAWRENCE YORK SPEAR, OF GROTON, CONNECTICUT, ASSIGNOR TO ELECTRIC BOAT COMPANY, OF GROTON, CONNECTICUT, A CORPORATION OF NEW JERSEY.

GUN MOUNTING FOR SUBMARINES.

Application filed July 28, 1924. Serial No. 728,644.

To all whom it may concern:

Be it known that I, LAWRENCE YORK SPEAR, a citizen of the United States, residing at Groton, in the county of New London, 5 State of Connecticut, have invented certain new and useful Improvements in Gun Mountings for Submarines; and I do hereby declare the following to be a full, clear, and exact description of the invention, such as 10 will enable others skilled in the art to which it appertains to make and use the same.

This invention relates to gun mounting for submarines, the principal object of the invention being to provide a mounting such 15 that the gun can be trained and operated with maximum efficiency while the entire submarine, with the exception of the conning tower and parts associated therewith, is submerged. In general this object is accomplished by providing a bridge substantially flush with the top of the conning tower, and mounting a non-recoil gun on the bridge adjacent to the conning tower. Means are provided for raising and lowering 20 the gun, and a platform fixed with respect to the conning tower and its spray-shield and located at a point above the bridge is provided in close proximity to the gun mounting so that the gun can be loaded and 25 operated from this platform. My invention makes it possible to use a larger gun than is commonly employed, and the effectiveness of the submarine is materially increased by virtue of the increased height of the gun 30 above the deck of the vessel.

The ordinary practice in mounting a gun on a submarine is to place the gun on the deck in front of the conning tower. This makes it necessary to expose the upper portion 40 of the submarine when the gun is in use in order to make it possible to reload the gun from the deck and to raise the gun above the surface of the water to the required height. It is thus apparent that the 45 ordinary practice of mounting a standard gun on the deck of a submarine is open to a number of objections, the most important of which are the relatively large area exposed to vertical and horizontal gun fire due to the 50 fact that the conning tower and a large portion of the deck are exposed when the submarine is in the firing position, the considerable amount of time required to pass from submerged to firing position and from firing 55 to submerged position due to the fact that

a large part of the submarine must be raised above the water or submerged, as the case may be, and the limited height to which the gun can be raised above the water level. Owing to the weight and the recoil forces 60 of the standard type of gun usually employed, guns of the desired caliber and power cannot be mounted very far above the deck without seriously decreasing the stability of the boat and seriously increasing 65 its submerged resistance.

I have found that the disadvantages of the ordinary gun mounting can be largely avoided by employing a non-recoil gun and mounting it above the conning tower and in 70 such a manner that the gun can be raised and lowered as desired. By using a non-recoil gun, of any standard type, and providing means for raising and lowering the gun, it is possible to mount the gun so that 75 when it is in its firing position it occupies a position at considerable distance above the deck of the vessel, without subjecting the gun support and associated parts to excessive stress when the gun is fired. I prefer to 80 provide a fixed platform above the level of the top of the conning tower and to mount the gun so that it can be raised and lowered as desired, the gun in its lowered or 85 housed position being just above the level of this platform. With the gun mounted in this manner, it is possible to raise the gun more than twice as high as the maximum elevation of the ordinary deck gun without exposing to gun fire any greater portion 90 of the submarine, and it is possible to operate the gun at the usual elevation above the water without exposing any part of the submarine except the conning tower. The 95 various objects and advantages of my invention will be apparent upon considering the following detailed description which is to be taken in conjunction with the accompanying drawings, in which:

Fig. 1 is a diagrammatic longitudinal section of a submarine conning tower and bridge, provided with the improved gun mounting; and

Fig. 2 is a top plan view of the submarine conning tower and gun mounting shown in 105 Fig. 1.

In Figs. 1 and 2 of the drawing, 1 indicates the deck of a submarine, and 2 the conning tower enclosed within the sheers 3. A hatch 4 is provided for the purpose of 110

giving access to the conning tower 2 from the control room located directly below the conning tower, and a second hatch 5 provides access to the bridge 6 from the conning tower. The bridge extends well forward from the conning tower so as to provide ample space for the gun mounting hereinafter described, and the bridge is enclosed within the spray shield 7 which extends upward so as to protect the personnel when the bridge is occupied and to serve as a fair-water for various fittings projecting above the top of the conning tower. The upper ends of the periscopes 8 and 9 extending up from the control room are enclosed within the periscope sheers 10, except when the periscopes are raised to their operative positions. In accordance with the usual practice, a compass 11 is provided on the bridge, the arrangement being such that the compass can be read from the conning tower as well as from the bridge.

As stated above, I prefer to construct the bridge so that it extends well forward from the conning tower, the bridge 6 being substantially flush with the top of the conning tower 2. The bridge is constructed in this manner so as to provide ample space for the gun mounting. In Fig. 1, I have shown the cylinder 12 of a gun hoisting apparatus mounted in the bridge 6 and within the conning tower sheers 3. The drawings, which are largely diagrammatic, show the cylinder 12 and a plunger 13 adapted to slide therein. The plunger 13 can be raised and lowered by regulating the supply of air, gas or liquid under pressure to the cylinder 12 in any well known manner. The plunger 13 carries a gun support 14, shown in the form of a yoke adapted to support the trunnions 15 of the gun 16.

The gun 16 can be of any common type, but I prefer to use a non-recoil gun. The gun 16, represented diagrammatically in the drawings, is such a non-recoil gun having a reaction or compensating device 17 thereon. Any suitable type of non-recoil gun which automatically compensates, to a greater or lesser extent, for the reaction caused by firing the projectile can be used.

In the accompanying drawings, I have shown a platform 18 located at a point above the bridge 6 substantially flush with the top of the spray shield 7. This platform 18 has a recess 19 in the center thereof adapted to receive the yoke 14 comprising the gun support, it being understood that the piston 13 to which the yoke 14 is connected passes thru the platform 18. This arrangement has been found to be quite satisfactory but it will be understood that the gun mounting can be located in some other relation to the platform without in any way departing from the spirit of my invention. Furthermore, while I prefer to construct the platform 18

so that its outline is somewhat as indicated at Fig. 2, yet it will be understood that the shape of the platform can be varied in many ways. The important consideration is to provide a platform, preferably stationary, on which the gunner can stand while reloading the gun and training the same. A ladder 20 extending from the bridge to the top of the platform 18 provides ready access to the platform from the bridge. In order to render the platform 18 as safe as possible a number of stanchions 21 are provided around the edge of the platform for the purpose of supporting a flexible or rigid railing 22. These stanchions 21 are preferably hinged to the platform so that when the gun 16 is lowered to its housed position the stanchions can be folded down as indicated by the dotted lines in Fig. 1 so that no part thereof projects above the gun.

Ammunition can be raised to the bridge from the ammunition room by means of a hoist 23. As shown in the drawing, this hoist consists of an inclined tube within the conning tower sheers 3 containing a chain or other suitable conveyor operated by any convenient means. The ammunition is placed in the lower end of the tube and the conveyor carries it to the top where it displaces the hinged cover 24 and is discharged onto the bridge adjacent to the gun mounting and the top of the conning tower. If it is so desired, a number of receptacles (not shown) can be arranged on the bridge 6 or on the platform 18 for temporarily storing the ammunition supplied to the bridge from the ammunition room.

The value of having a non-recoil gun mounted in the manner above described is apparent when consideration is given to the fact that a submarine provided with such a gun mounting can be passed from submerged to firing position in less than one thirty-fifth of the time required to raise a submarine equipped with an ordinary deck gun from submerged to firing position. Furthermore, the gun mounted as above described can be raised to the usual elevation above the water without exposing any portion of the submarine except the conning tower. The conning tower can be armored, if it is so desired, thus reducing to a minimum the hazards incident to raising the submarine to firing position.

It is to be understood that the various features of my invention can be modified without departing from the spirit of the invention which is not limited to the particular embodiment illustrated and described but includes such modifications thereof as fall within the scope of the appended claims. For example, while I prefer to construct the stationary platform 18 and the bridge spray-shield 7 so that the former is substantially flush with the top

of the latter, yet it will be understood that the spray-shield can be constructed so as to extend above the platform 18 in which case the stanchions 21 and the railing 22 can be eliminated.

I claim:

1. The gun mounting for submarines, comprising the combination with the bridge of a submarine, of a gun supported by the 10 bridge, a platform above said bridge, and means for hoisting the gun above the platform.

2. The gun mounting for submarines, comprising the combination with the conning tower of a submarine, of a bridge substantially flush with the top thereof, a gun mounted on said bridge adjacent to the conning tower, and means for hoisting said gun into firing position above the top of the 20 conning tower.

3. The gun mounting for submarines, comprising the combination with the conning tower of a submarine, of a bridge substantially flush with the top thereof, a gun 25 mounted on said bridge adjacent to the conning tower, a platform rigidly mounted above said bridge, and means for hoisting said gun above said platform into firing position.

4. The gun mounting for submarines, comprising the combination with the conning tower of a submarine, of a bridge substantially flush with the top of the conning 30 tower, a gun support mounted on said bridge adjacent to the conning tower, a gun carried by said support, a platform above the bridge and having an opening therein thru which the gun support extends, and means for moving said gun support with respect 35 to said platform.

5. The gun mounting for submarines, comprising the combination with the conning tower of a submarine, of a bridge substantially flush with the top of the conning 40 tower, a gun support mounted on said bridge adjacent to the conning tower, a gun carried by said support, a platform above the bridge and having an opening therein thru which the gun support extends, and means for raising the gun into firing position and 45 for lowering it onto said platform.

6. The gun mounting for submarines, comprising the combination with the conning tower of a submarine, of conning tower 50 sheers, a bridge substantially flush with the top of the conning tower, a gun mounted on said bridge adjacent to the conning tower, a platform rigidly mounted above said bridge, and means within the conning tower sheers 55 for raising and lowering said gun.

7. The gun mounting for submarines, comprising the combination with the conning tower of a submarine, of conning tower 60 sheers, a bridge substantially flush with the top of the conning tower, a gun mounted on

said bridge adjacent to the conning tower, a platform rigidly mounted above said bridge, and means within the conning tower sheers and below said platform for hoisting said gun into firing position.

70

8. The gun mounting for submarines, comprising the combination with the conning tower of a submarine, of a bridge substantially flush with the top of the conning tower, a gun mounted on said bridge adjacent to the conning tower, and means for hoisting ammunition to said bridge adjacent to said gun.

75

9. The gun mounting for submarines, comprising the combination with the conning tower of a submarine, of a bridge substantially flush with the top of the conning tower, a gun mounted on said bridge adjacent to the conning tower, means for hoisting ammunition to said bridge adjacent to 80 said gun and means for hoisting said gun into firing position above the top of the conning tower.

85

10. The gun mounting for submarines, comprising the combination with the conning tower of a submarine, of conning tower sheers, a bridge substantially flush with the top of the conning tower, a gun mounted on said bridge adjacent to the conning tower, and means extending within the conning 90 tower sheers for hoisting ammunition to said bridge adjacent to said gun.

95

11. The gun mounting for submarines, comprising the combination with the bridge of a submarine, of a gun supported by a bridge, a platform above said bridge, means for hoisting the gun above the platform, and hinged guide rail stanchions secured to 100 said platform.

105

12. The gun mounting for submarines, comprising the combination with the bridge of a submarine, of a gun supported by the bridge, a platform above said bridge, and a spray-shield extending up substantially flush with said platform.

110

13. The gun mounting for submarines, comprising the combination with the bridge of a submarine, of a gun supported by the bridge, a platform above said bridge, means for hoisting said gun above said platform, a spray-shield extending up substantially flush with said platform and hinged guide rail stanchions secured to said platform.

115

14. The gun mounting for submarines, comprising the combination with the bridge of a submarine, of a non-recoil gun supported by the bridge, a platform above said bridge and means for hoisting the gun above the platform.

120

15. The gun mounting for submarines, comprising the combination with the conning tower of a submarine, of a bridge substantially flush with the top thereof, a non-recoil gun mounted on said bridge adjacent to the conning tower, a platform rigidly 125

130

mounted above said bridge, and means for hoisting said gun above said platform into firing position.

16. The gun mounting for submarines, comprising the combination with the conning tower of a submarine, of a bridge substantially flush with the top of the conning tower, a gun support mounted on said bridge

adjacent to the conning tower, a non-recoil gun carried by said support, a platform ¹⁰ above the bridge having an opening therein thru which the gun support extends, and means for moving said gun support with respect to said platform.

In testimony whereof I affix my signature.
LAWRENCE YORK SPEAR.
